UNITED STATES PATENT OFFICE.

EDWARD F. CALDWELL, OF LARCHMONT, NEW YORK.

DESIGN FOR A PORTFOLIO-COVER.

42,352.

Specification for Design.

Patented Mar. 26, 1912.

Application filed December 30, 1911. Serial No. 668,774. Term of patent 3½ years.

To all whom it may concern:

Be it known that I, EDWARD F. CALDWELL, a citizen of the United States, and a resident of Larchmont, in the county of Westchester and State of New York, have invented a new, original, and ornamental Design for Portfolio-Covers, of which the following is a specification, reference being had to the accompanying drawing, forming a part thereof.

The figure is a plan view of a portfolio showing my new design.

I claim—

The ornamental design for a portfolio cover as shown.

EDWARD F. CALDWELL.
